SPARK PLUG SHIELD

Joseph J. Mascuch, Newark, N. J.

Original application July 11, 1931, Serial No. 550,076. Divided and this application February 17, 1933, Serial No. 657,166

9 Claims. (Cl. 123—169)

This invention relates to spark plug shields and is a division of application Serial No. 550,076, filed July 11th, 1931.

When internal combustion engines using electrical ignition systems are used in proximity to radio receiving apparatus, there is a radiation of electrical waves from the ignition system, which radiation causes interference with the reception of radio equipment.

By properly surrounding with a conductive casting, all of the parts of the ignition system through which high frequency currents pass and grounding the said conducting casing, it is possible to dissipate the energy of the electrical radiations directly to ground, thereby preventing the aforesaid interference. It is an object of this invention to provide a conductive casing or shielding for the spark plugs of internal combustion engines, whereby interference to radio communication equipment installed in proximity to the engine will be eliminated.

This invention is applicable to all types of combustion engines and particularly to engines on units such as aeroplanes, motor boats, automobiles, submarines, etc.

It is also desirable to prevent outside electrical impulses from affecting the spark plugs. Therefore, another object of the invention is to provide a shield for a spark plug which will intercept and ground any electrical impulses coming from the outside.

Where exposed spark plugs are used they are subject to breakdowns by reason of the effect of oil, water, gasoline, or the accumulation of foreign matter. Where the spark plugs are used on aeroplanes a breakdown or short in the plug will cause serious damage. Therefore, another object of the invention is to provide a shield to surround a spark plug which will prevent water, gasoline or other foreign substances from reaching the plug.

Where the spark plugs are used on aircraft engines at high altitudes or under other conditions of low atmospheric pressure, at which time the conduction of the surrounding air is very much greater than the conduction of the compressed gas between the gap of the spark plug points, there is danger of the ignition current flashing over or sparking to a nearby grounded conductor and natural sparking outlet at spark plug points. It is standard practice to maintain a distance of at least $\frac{5}{8}$ ths of an inch between any uninsulated conductor carrying ignition current from any grounded part. In providing a shielding means for the spark plug, it would be necessary to use a large and bulky grounded conductor to enclose the spark plug, unless other insulating means is pro-

vided. It is therefore a further specific object of this invention to provide a shielding means of moderate size for the spark plug which will provide a distance of at least $\frac{5}{8}$ ths of an inch between all uninsulated parts carrying high tension ignition current from surrounding grounded parts. Changes of temperature will cause condensation of moisture on the insulating body of the spark plugs and snow, water or ice which may leak through the shielding means and gather on the insulated body of the spark plug will cause a short circuit and make it extremely difficult to start the engine without first wiping off all moisture from the insulated body of the spark plug and spark plug leads. It is therefore a further specific object of this invention to provide a waterproof and airtight shielding means for the spark plugs. Furthermore, by providing a moisture-proof shield the air spaces inside may be filled with a suitable, semi-solid dielectric such as petroleum jelly to increase the insulating qualities of the shield.

A further object of the invention is to provide a container for a spark plug which may be adapted to receive various types of unshielded spark plugs.

The invention consists of the construction, combination and arrangement of parts as herein illustrated, described and claimed.

In the accompanying drawing, forming part hereof, is illustrated one form of embodiment of the invention, in which drawing similar reference characters designate corresponding parts, and in which:

Figure 1 is a vertical section taken approximately on line 1—1 of Figure 2 looking in the direction indicated by the arrows; and,

Figure 2 is a front elevation, partly broken away, of a spark plug shield.

The current is supplied from the distributors through conductors 39 encased in insulation 40. The conductors are carried in shielded conduits 41 provided on their ends with ferrules 50 having shoulders 52 in contact with the spark plug shield so that a continuous grounded circuit is formed around the spark plugs and conductors.

The spark plug shield is designated generally 45 as 69 and comprises an open-bottomed cup 70 to surround the spark plug 68. The cup 70 may be made longer or shorter to accommodate various types of unshielded plugs 68. The cup 70 is provided with an inwardly tapered bottom portion 71 so that it may be easily seated on the cylinder head of the engine. The tapered portion 71 terminates in an inturned annular flange 72. The flange 72 is adapted to abut the lower skirt of the plug 68. A copper washer 73 may

be secured inside the cup 70 above the flange 72 so as to insure sealing contact of the plug 68 with the cylinder head of the engine. The cup 70 is made sufficiently large to allow a socket wrench to be used to screw the plug 68 firmly into place. When the plug 68 is screwed into place the cup 70 will be rigidly held thereabout, and in electrical contact with the engine. On the upper edge of the cup 70 an annular projecting flange 74 is provided by bending the metal upon itself and a supporting shoulder 75 is formed by bending the metal of the cup 70 outward and downward. Before the end 76 of the cup 70 is turned inward as shown in Figure 1, an annular L-shaped band of steel or other metal 77 is placed in the housing formed by bending the cup 70 and the end 76 is then bent inward to hold the ring 77 in place. With this construction a firm foundation is provided 20 for the shoulder 75 with the use of the least possible material so as to reduce the weight.

Disposed over the cup 70 is a cap 78 formed or molded of dielectric material such as bakelite. The cap 78 is electro-plated or otherwise 25 covered with metallic foil or other conductive means 79 to protect the cap 78 and also to serve as an electrical conductor. On the lower end of the cap 78 is formed an annular depending flange 80 with a recess 81 adjacent thereto. A 30 special compound washer 82 is disposed in the recess 81 so that when the cap 78 is disposed on the cup 70 the flange 74 on the cup 70 will ride against the washer 82 to make a moisture-proof seal. At the same time the depending 35 flange 80 on the cap 78 will be in electrical contact with the shoulder 75 on the cup 70. A reinforcing member 83 is disposed in the top of the molded cap 78.

On one side of the cap 78 is disposed a screw-threaded bushing 84 the inner face of which is beveled as shown at 85 to receive the tapered face of a conical washer 54. The portion of the cap 78 adjacent the conical washer 54 is also beveled so that the washer 54 will make a sealing contact against the cap 78 and the bushing 84. A collar nut 42 is used to hold the conduit 41 to the bushing 84.

Through the center of the bushing 84 and through the cap 78 is an opening 86 to accommodate the conductor 39 with the insulation 40. The opening 86 is made at an angle to the spark plug 68 so that the conductor 39 and conduit 41 will not be bent between the outlet 33 on the manifold 25 and the spark plug 68. The conductor 39 is usually made of strand wire and the ends of the strands of the conductor 39 are formed into one piece by solder 87, for the purpose hereinafter shown.

Set in the molded cap 78 immediately above the spark plug 68 is an interiorly screw-threaded bushing 88. A screw 89 is disposed through the bushing 88 and is provided with a sharp point 90. The point 90 of the screw 89 is adapted to be forced through the insulation 40 and make 65 contact with the conductor 39. The ends of the conductor 39 being held together by the solder 87 the point 90 will spread the strands of wire as it is forced through and will insure a good electrical contact.

Carried by the lower end of the screw 89 is a 70 coil spring 91. The upper end of the coil spring 91 may be soldered to the screw 89 and the lower end of the spring 91 is adapted to make contact with the stem of the spark plug 68.

The cap 78 being formed of dielectric material

such as bakelite a short dependent skirt 92 is provided adjacent the upper portion of the spark plug 68 and a second longer skirt 93 is provided adjacent the wall of the cup 70. The skirt 92 serves as a container for the spring 91.

The skirts 92 and 93 are adapted to prevent high tension flashes from the spark plug 68 to the cup 70. In flying at high altitudes in rarefied air these flashes will occur very frequently unless some means such as the skirts described are used to prevent them. With the spark plug shielding means here described it has been found very successful to fill the spaces in the cup 80, designated generally as 98, with a petroleum jelly or other semi-solid dielectric. This is made possible by reason of the fact that the cup 70 and the cap 78 are entirely moisture-proof and will retain the petroleum jelly therein. By this method the flashes from the plug to the cup 70 are eliminated and a cooling means is afforded for the spark plug.

The cap 78 is held onto the cup 70 by means of a spring bail 94 the ends of the bail 94 being disposed through the shoulder 75 and the ring 77. In screwing the spark plug 68 into position the cup 70 will be turned around and the bail 94 will not always be in proper position to hold down the cap 78. Therefore, a series of openings 95 are provided so that the bail 94 may be placed in any desired position. The ring 77 acts as a bearing for the bail 94 and prevents the distortion of the openings 95 by the bail 94. At the top of the bail 94 is provided a ball 96 which is free to rotate on the bail 94. When the cap 78 is placed on the cup 70 the spring 91 is compressed and exerts tension against the cap 78. The ball 96 is provided on the bail 94 so that the bail 94 may be easily swung to the top of the cap 78 and seated in a recess 97 provided therefor. With the construction the bail 94 will at all times hold the cap 78 firmly on the cup 70 but will allow the cap 78 to be quickly removed at any time.

Having thus fully described the invention what is claimed as new and desired to be secured by Letters Patent is:

1. A spark plug shield comprising a cup to enclose a spark plug, said cup having a shoulder formed on the upper edge thereof, a reinforcing member disposed within said shoulder, a cap to seat on said shoulder and means carried by said shoulder to maintain the cap on the cup.

2. A spark plug shield comprising a cup to enclose a spark plug, said cup having a shoulder formed on the upper edge thereof, a reinforcing member disposed within said shoulder, a cap to seat on said shoulder and means pivoted in said shoulder to maintain the cap on the cup.

3. A spark plug shield comprising a cup to enclose a spark plug, said cup having a shoulder formed on the upper edge thereof, a reinforcing member disposed within said shoulder, a cap to seat on said shoulder and a bail carried by said shoulder and provided with a rotatable member to seat on said cap to hold the cap on the cup.

4. A spark plug shield comprising a cup to enclose a spark plug, said cup having a shoulder formed on the upper edge thereof, a reinforcing member disposed within said shoulder, a cap to seat on said shoulder, said shoulder and reinforcing member being provided with a plurality of openings and a retaining member to be selectively disposed in some of said openings to maintain the cap in position on the cup.

5. In a spark plug radio shield, a shielding cap

adapted to be placed over a spark plug comprising a dielectric body formed with a bore to receive an ignition conductor, a contact means carried by the cap in contact with a spark plug and projecting into said bore to contact the ignition conductor, said cap being formed with a relatively short dielectric skirt to surround the contact means and a relatively long dielectric skirt to surround the upper portion of a spark plug and a metallic sheath on the outside of the dielectric body.

6. In a radio shield for spark plugs, a shielding cap adapted to be positioned over a spark plug comprising a metal shell, a body of dielectric material within the shell, said body having a lateral opening to receive a conductor and said body being formed with a circular recess in alignment with the upper end of a spark plug, and a partially resilient contact means carried by the dielectric body and seated in said recess, said contact means being adapted to project into the lateral opening to contact a conductor.

7. In a radio shield for spark plugs, a shielding cap adapted to be positioned over a spark plug comprising a metal shell, a body of dielectric material within the shell, said body having a lateral opening to receive a conductor and contact means carried by the body, the lower edge of said metal shell terminating in a depending flange adapted to make electrical contact with a

complementary element of the radio shield and said lower edge of the shell being formed with an annular recess to receive a liquidproofing packing.

8. A spark plug radio shield comprising, in combination, a cup to surround a spark plug, the upper end of said cup terminating in an annular flange with a seat adjacent thereto, a cap to cover said cup comprising a metallic shell, a dielectric body in said shell, said shell and body being formed with an opening to receive a conductor, contact means carried by the dielectric body, the lower edge of said shell having a depending flange adapted to seat on the cup in electrical contact therewith, the annular flange on the cup being adapted to enter an annular recess on the cap adjacent the depending flange to make a liquidproof connection between the cup and the cap and means to hold the cap on the cup.

9. A spark plug radio shield comprising, in combination, a cup to surround a spark plug and a cap to cover the cup, said cap comprising a dielectric body, a metallic covering and contact means and a bail carried by the cup to removably hold the cap on the cup, the top of said cap being formed with a detent to receive the bail and having a reinforcing means carried in said dielectric body adjacent the detent.

JOSEPH J. MASCUCH. 30
